UNITED STATES PATENT OFFICE

JOHN F. CROWLEY, OF LYNN, MASSACHUSETTS, ASSIGNOR TO UNITED SHOE MACHINERY CORPORATION, OF PATERSON, NEW JERSEY, A CORPORATION OF NEW JERSEY

SHOE AND SHANK PIECE THEREFOR

Application filed October 25, 1929. Serial No. 402,499.

This invention relates to improvements in shoes and shank pieces therefor and to improvements in methods of making shoes. The invention is herein illustrated with relation to a turn shoe having a shank piece which is riveted to the shoe sole, although in certain aspects the invention is useful also in connection with other types of shoes such, for example, as welt shoes, as well as McKay-sewed or other shoes in which a tread sole is directly secured to the upper.

In United States Letters Patent No. 1,695,577, granted December 18, 1928, upon application of William G. Dodge, there is disclosed a turn shoe having a composite shank piece which is riveted to the sole, the shank piece comprising a filler member of more or less flexible material, such as leather or leatherboard, and a metallic reinforcing or stiffening strip which is secured to the outer side of the filler piece, the rivet extending inwardly through the sole of the shoe and through preliminarily formed registering apertures in the reinforcing strip and in the filler piece, with the inner end of the rivet clenched against the inner surface of the filler piece and with the head of the rivet flush with the outer surface of the sole where it is a more or less prominent feature of the finished shoe.

One object of the present invention is to provide a shoe which has a riveted shank construction but in which the rivet is entirely concealed from view from the outside of the shoe.

With this object in view, one feature of the invention consists in the provision of a shoe, illustrated as a turn shoe, and comprising, as herein shown, a sole, a shank piece filler member overlying the heel and shank portions of the sole, a shank piece reinforcing member located between the filler member and the sole and secured to the filler member, said reinforcing member having a single circular aperture therein, a heel secured to the sole and the filler member, and a rivet arranged with its head located between the reinforcing member and the filler member and having a tubular shank portion of substantially the same diameter as the aperture in the reinforcing member extending through

and fitting tightly within said aperture, and firmly securing together the sole and the reinforcing member.

In one of the illustrated embodiments of the invention special provision is made for concealing the inner as well as the outer end of the rivet, the construction being such that a metallic strip, constituting the reinforcing member of the shank piece, is firmly secured at its ends to the filler member, and the rivet extends through and has holding engagement at its inner end only with the metallic strip, the filler member having no rivet-receiving aperture therein and serving to cover the inner end of the rivet and effectively to conceal it from view from the inside of the shoe even if the sock lining is removed.

In still another aspect the invention consists in the provision of a composite shank piece for use in a turn shoe which, as herein illustrated, comprises a filler member, a reinforcing member secured to the filler member and having a single circular aperture therein, and a rivet arranged with its head located between said members and having a tubular shank portion of substantially the same diameter as said aperture with its barrel extending through said aperture and projecting beyond said reinforcing member to be passed through and fastened to the sole of a shoe.

The invention further resides in an improved method of making shoes which consists in inserting the barrel of a rivet through an aperture in a shank stiffening member, attaching the shank stiffening member to a shoe bottom member with the head of the rivet located between said members, splitting a tread sole to provide a flap at the outer side of the sole, punching a hole through the body of the sole beneath the flap in position to receive the rivet, projecting the barrel of the rivet through the aperture in the tread sole, clenching the outer end of the rivet against the outer side of the body of the sole, and laying the sole flap to cover the rivet and the breast of a heel attached to the shoe.

The invention will be explained in reference to the accompanying drawing, in which Fig. 1 is a longitudinal sectional view of a

turn shoe constructed in accordance with the present invention;

Fig. 2 is a cross-sectional view on the line II—II of Fig. 1;

Fig. 3 is a perspective view of the shank piece shown in Figs. 1 and 2; and

Fig. 4 is a fragmentary sectional view illustrating a modification of the construction shown in Figs. 1 and 2.

Referring to the drawing, there is shown in Fig. 1 a turn shoe 6 having an upper 8 and bottom members comprising a sole 10 and a composite shank piece 12, and having also a heel 14 secured by means of nails 16 to the heel seat of the shoe in the usual manner. The breast of the heel 14 is covered by a flap 18 which is split from an integral with the sole 10. The inside of the shoe bottom is covered by a sock lining 20. The shank piece 12, which has the usual longitudinally arched formation, consists of a filler member or shoe bottom member 22 of such material as leather or leatherboard and a metallic stiffening or reinforcing strip 24 which is secured at its end portions by means of prongs 26 to the filler member 22.

It is desirable firmly to secure together the shank piece and the sole at the shank portion of the shoe. As herein shown, in Figs. 1 and 2 the shank piece is secured to the sole approximately at the middle of its shank portion by means of a tubular rivet 28 and provision is made for insuring that the rivet shall be covered and concealed from view both from the inside and from the outside of the shoe. To this end, a rivet-receiving hole 30 is preliminarily formed in the stiffening strip 24 and the rivet 28 is inserted through the hole 30 before the stiffening strip is attached to the filler member 22, the rivet being inserted from the longitudinally convex side of the stiffening strip 24 so that the head of the rivet will be located between the strip 24 and the filler member and will bear against and be covered by the filler member. To provide for holding attachment of the rivet with the sole of the shoe without, however, having the outer end of the rivet visible at the outer or tread side of the sole, the heel-breast-covering flap 18 is made to continue forwardly beyond the heel-seat portion of the sole to a point just forward of the location where the rivet is to be passed through the sole, and a hole 32 (Fig. 1) is made in the body portion of the sole beneath the flap 18 to receive the rivet. The location of the hole 32 in the sole may be determined by preliminarily inserting the shank piece and rivet in proper position inside the shoe and applying sufficient pressure to the portion of the filler member above the rivet to cause the unset outer end of the rivet to make a slight mark or depression in the inner surface of the sole, after which the shank piece may be removed and a hole bored from the inside of the shoe in the location de-

termined by the mark. Thereafter the shank piece is replaced in the shoe with the rivet projecting through the hole 32 in the sole and the outer end of the rivet is clenched over the outer surface of the body portion of the sole, beneath the flap 18, thus firmly securing together the sole and shank piece. Inasmuch as the shank portion of the rivet fills or fits tightly within the hole 30 in the stiffening strip 24 undesirable relative displacement of the shank piece and the sole is prevented.

After the rivet 28 has been set or clenched, the sole flap 18 is laid and adhesively secured in place against the shank portion of the sole and the breast surface of the heel, thereby completely covering and concealing the clenched-over outer end of the rivet and covering the heel breast. As herein shown the flap 18 is formed so as to provide a relatively thick portion 19 near where it is connected with the sole for covering the rivet and a relatively thin portion for covering the heel breast.

As shown, the filler member 22 covers and conceals from view the head or inner end of the rivet. Inasmuch as the filler member 22 is made of relatively thick and heavy material no protuberance will be formed therein by the head of the rivet even after the shoe has been worn, and consequently, there will be nothing visible from the inside of the shoe to indicate or suggest the presence of the rivet in the shank portion of the sole. If desired however, the rivet, instead of extending through the reinforcing or stiffening strip only, may be extended also through the filler piece 22. Such a construction is shown in Fig. 4, wherein a rivet 280 extends through an outsole 10 and through both the reinforcing member 24 and the filler member 22 of a shank piece 12, the head or outer end of the rivet being covered by the relatively thick portion 19 of a flap 18 split from the sole 10 while the inner end of the rivet is clenched against the inner surface of the filler member 22 and is covered by a sock lining 20.

For use in the manufacture of turn shoes wherein it is desired to have the head or the inner end of the rivet covered by the filler member of a composite shank piece, the shank piece may be made and shipped to the shoe manufacturer in the form shown in Fig. 3 wherein the rivet 28 is arranged with its head located between the reinforcing member 24 and the filler member 22 and with its barrel extending only through the reinforcing member. In using a composite shank piece of the type just described in the making of a turn shoe the sole of the shoe is split at its outer side to a point somewhat forward of the front of the heel seat and the body portion of the sole beneath the flap is punched to provide an aperture properly located to receive the rivet in the shank piece. Thereafter, the shank piece is placed inside of the shoe and

the projecting barrel of the rivet is inserted through the aperture in the sole and its outer end clenched against the outer surface of the body portion of the sole. Thereafter the 5 heel is attached and the sole flap is laid so as to conceal the clenched end of the rivet and cover the breast of the heel.

Having described my invention, what I claim as new and desire to secure by Letters

10 Patent of the United States is:

1. A turn shoe comprising, in combination, an upper, a sole having a flap split from its outer side and integrally connected at its forward end with the body of the sole, a shank piece filler member overlying the heel and shank portions of the sole, a shank piece reinforcing member located between the filler member and the sole and secured to the filler member, said reinforcing member having a 15 single circular aperture therein, a rivet firmly securing said reinforcing member to the sole, said rivet being arranged with its head located between the reinforcing member and the filler member and having a cylindrical shank portion of substantially the same diameter as the aperture in the reinforcing member extending through and fitting tightly within said aperture, and a heel attached to the sole, the outer end of the rivet and the 20 breast of the heel being covered by said sole flap.

2. A turn shoe comprising, in combination, an upper, a sole, a shank piece filler member overlying the heel and shank portions of the sole, a shank piece reinforcing member located between the filler member and the sole and secured to the filler member, said reinforcing member having a single circular aperture therein, a heel secured to the sole and the 25 filler member, and a rivet arranged with its head located between the reinforcing member and the filler member and having a tubular shank portion of substantially the same diameter as the aperture in the reinforcing member extending through and fitting tightly within said aperture and firmly securing together the sole and the reinforcing member.

3. A shoe comprising, in combination, an upper, a tread sole, a shoe bottom member, a heel secured to the tread sole and to the shoe bottom member, a shank stiffener located between the tread sole and the shoe bottom member and secured to the latter, said shank 30 stiffener having a single circular aperture therein, a rivet firmly securing said reinforcing member to the tread sole, said rivet having a cylindrical shank portion of substantially the same diameter as the aperture in the reinforcing member extending through and fitting tightly within said aperture, and means integral with the tread sole concealing from view the outer end of the rivet and covering the breast of the heel.

4. As an article of manufacture, a com-

posite shank piece for use in a turn shoe comprising, in combination, a filler member, a reinforcing member secured to the filler member and having a single circular aperture therein, and a rivet arranged with its head located between said members and having a tubular shank portion of substantially the same diameter as said aperture extending through and fitting tightly within said aperture and projecting beyond said reinforcing member to be passed through and fastened to the sole of a shoe.

5. That improvement in methods of making shoes which consists in inserting the barrel of a rivet through an aperture in a shank stiffening member, attaching the shank stiffening member to a shoe bottom member with the head of the rivet located between said members, splitting a tread sole to provide a flap at the outer side of the sole, punching a hole through the body of the sole beneath the flap in position to receive the rivet, projecting the rivet through the hole in the tread sole, clenching the outer end of the rivet against the outer side of the body of the sole, 80 and laying the sole flap to conceal the rivet and cover the breast of a heel attached to the shoe.

6. That improvement in methods of making turn shoes which consists in splitting a flap from the outer side of the heel and shank portions of the sole of a turn shoe and perforating the body of the sole to provide a rivet-receiving hole in the shank portion of the sole, placing within the shoe a composite shank piece comprising a filler member and a perforated reinforcing member having a rivet arranged with its barrel extending through the perforation in said reinforcing member and with its head located between said members, inserting the outer end of the barrel of the rivet through the hole in the sole, clenching the outer end of the rivet against the body of the sole, and laying the flap to conceal the rivet and cover the breast of a heel attached to the shoe.

7. That improvement in methods of making turn shoes which consists in splitting a flap from the outer side of the heel and shank portions of the sole of a turn shoe, placing in position within the shoe a composite shank piece comprising a filler member and a perforated reinforcing member having a rivet arranged with its barrel extending through the perforation in said reinforcing member and with its head located between said members and forcing the barrel of the rivet against the sole of the shoe to make a locating mark on the inside of the sole, removing the shank piece and boring through the sole from the inside of the shoe in the location determined by said mark to make a hole through the body portion of the sole, replacing the shank piece in the shoe and projecting the barrel of the rivet through the hole.

in the sole, clutching the outer end of the rivet against the body portion of the sole, and laying the flap to conceal the rivet and cover the breast of a heel attached to the

shoe.

In testimony whereof I have signed my name to this specification.

JOHN F. CROWLEY.
